UNITED STATES PATENT OFFICE.

THOMAS CARENCE, OF KANSAS CITY, MISSOURI.

PENCIL-HOLDER.

1,102,242.

Specification of Letters Patent.

Patented July 7, 1914.

Application filed March 23, 1914. Serial No. 826,497.

To all whom it may concern:

Be it known that I, THOMAS CARENCE, a citizen of the United States, residing at Kansas City, in the county of Jackson and 5 State of Missouri, have invented a certain new and useful Improvement in Pencil-Holders, of which the following is a specification.

My invention relates to improvements in 10 pencil holders.

The object of my invention is to provide a pencil holder which is convenient to carry, which is inexpensive to manufacture, and which will securely hold a pencil and at 15 the same time guard the point thereof from injury.

Other novel features of my invention are hereinafter fully described and claimed.

In the accompanying drawings which 20 illustrate the preferred embodiment of my invention, Figure 1 is a perspective view of my improved pencil holder. Fig. 2 is a side elevation of the pencil holder, showing in dotted lines a pencil mounted therein. 25 Fig. 3 is a plan view of the blank from which the pencil holder is formed. Fig. 4 is a cross section on the line 4—4 of Fig. 2.

Similar reference characters designate similar parts in the different views.

30 1 designates the body of the pencil holder which is made, preferably, from a plate of sheet metal, such as brass, aluminum or steel, which possesses, at least, an amount of resiliency sufficient for the purpose hereinafter referred to.

In Fig. 3 is shown a blank from which the pencil holder is formed. Extending laterally from opposite edges of the body 1, as shown in Fig. 3, are extensions 2, which, 40 as shown in the other figure, are formed into rings 2' or hollow cylinders, the axes of which are parallel with the longitudinal edges of the body 1. Preferably the rings 2' are formed on the same side of the body 1.

45 One end of the body 1 is provided, as shown in Fig. 3, with two longitudinal extensions 3 which are first bent laterally on the line a—b of Fig. 3, and then again on the line c—d of Fig. 3, thereby forming two 50 resilient tongues 3', which extend respectively toward and are in alinement with the rings 2'. The free ends of the tongues 3' are respectively formed on the sides next to the body 1 into longitudinal channels 4 which are respectively adapted to receive 55 two pencils respectively mounted in and

extending through the rings 2', one of such pencils being shown in Fig. 2, and designated by 5. The tongues 3' are so spaced from the body 1, that they will be sprung outwardly from the body as shown in dotted lines in Fig. 2, when the pencils are inserted in the channels 4. The pencils will thus be securely held, while their points will be guarded by the transverse portions of the 60 tongues 3' at the bases thereof. 65

For attaching the pencil holder to a garment, I preferably attach to the rear side of the body 1 adjacent to the upper end thereof the upper end of a longitudinal resilient metal plate 6, the lower end of which is, preferably, slightly curved away from the body 1, to permit the ready insertion of the plate 6 through a button hole or into a pocket of a garment. 70

75 For the purpose of carrying a card, containing advertising matter or adapted to have memoranda inscribed thereon, the longitudinal edges of the body 1, above the rings 2' are inwardly turned so as to form 80 two longitudinal grooves 7 which are adapted to receive opposite edges of a card not shown, the card being insertible in the upper ends of the grooves 7.

I do not limit my invention to the structure illustrated and described, as modifications, within the scope of the appended claims, may be made without departing from the spirit of my invention. 85

Having thus described my invention, what 90 I claim and desire to secure by Letters Patent, is:—

1. A pencil holder comprising a body, a ring carried by the body at one side thereof for receiving therethrough a pencil, and a 95 resilient tongue extending over and carried by the body, with its free end adjacent to and in alinement with said ring, said free end having a channel on the side adjacent to the body adapted to receive and clampingly hold against the body said pencil. 100

2. A pencil holder comprising a sheet metal plate of resilient material, said plate having at one edge a lateral extension formed into a ring disposed at one side of 105 the body of the plate, the plate at one end having a resilient tongue extending laterally from the body of the plate, in alinement with said ring, and then toward said ring at the same side of the plate as the ring, the 110 free end of the tongue having on the side adjacent to the body of the plate a channel

adapted to receive and clampingly hold against the body a pencil extended through said ring.

3. A pencil holder comprising a body, two rings carried by the body at one side thereof for respectively receiving two pencils, and two resilient tongues carried by the body in alinement respectively with said two rings and having their free ends at the 10 sides adjacent to the body respectively formed into two channels adapted to respectively receive said two pencils and clampingly hold them against the body.

4. A pencil holder comprising a sheet 15 metal plate of resilient material having at opposite edges respectively two lateral extensions formed into rings adapted to receive therethrough respectively two pencils, the plate at one end being provided with 20 two tongues disposed respectively in alinement with said two rings, said tongues be-

ing first bent laterally and then extended respectively toward said rings, said tongues having at their free ends in the sides next to the body of the plate channels respectively for receiving said pencils. 25

5. A pencil holder comprising a body, a ring carried thereby at one side thereof for receiving a pencil, and a resilient tongue extending laterally from one end of the body 30 and then over the body in alinement with said ring at the same side of the body as the ring, the free end of the tongue being provided with means for embracing said pencil and holding it clamped against the body. 35

In testimony whereof I have signed my name to this specification in presence of two subscribing witnesses.

THOMAS CARENCE.
